UNITED STATES PATENT OFFICE.

GUNNAR H. RYDBERG, OF AUBURN, RHODE ISLAND.

SHADE SHIELD.

Application filed October 13, 1921. Serial No. 507,420.

To all whom it may concern:

Be it known that I, GUNNAR H. RYDBERG, a citizen of the United States, residing at Auburn, in the county of Providence and State of Rhode Island, have invented certain new and useful Improvements in Shade Shields, of which the following is a specification.

This invention relates to improvements in 10 a shade curtain-roller cover and cleaner adapted to be positioned above the usual shade-curtain roller, and the object of this invention is to support a suitable hood or cover over a shade curtain roll to prevent 15 dust from accumulating thereon, and to provide a lining for the hood adapted to engage the outer surface of the curtain on the roller to wipe off or remove any dust or dirt which may have collected on the curtain 20 when in extended position.

A further object of the invention is to provide suitable yielding means for supporting the hood whereby the cleaning lining may be caused to rest upon the surface of the curtain and to follow the changing diameter of the roller as the curtain is wound upon and unwound therefrom.

A still further object of the invention is to provide means whereby the cover or hood 30 may be readily removed to renew or clean its dust-wiping lining.

With these and other objects in view, the invention consists of certain novel features of construction, as will be more fully described, and particularly pointed out in the appended claims.

In the accompanying drawings.

Figure 1 is a front view showing a curtain roller mounted upon a window frame 40 and my protecting and cleaning device positioned over the roller.

Figure 2 is an end view of the curtain roller showing my device mounted thereover.

Figure 3 is a perspective view of the protecting hood.

Figure 4 is an enlarged view of the hood showing the arm-engaging loops raised from the plane of the surface also showing the edges of the stock as rolled inwardly over 50 the edges of the lining to retain the latter in position.

It is found in practice that ordinarily dust raised by sweeping and cleaning a room accumulates on the surface of a curtain roll 55 to such an extent that after a time the cur-

tain becomes discolored and so becomes unsightly and has to be replaced by fresh ones.

To overcome this objectionable feature I have invented a hood or cover adapted to set closely over a curtain roller to prevent 60 dust from settling on the curtain roll and in addition I have lined this hood or cover with a material which is adapted to engage the surface of the curtain on the roller and wipe off or remove any dust which may have 65 accumulated thereon as the curtain is being rolled up or unrolled, and the following is a detailed description of one means by which this result may be accomplished.

With reference to the drawings, 10 designates the hood or cover member of my device which may be made of any suitable material but which is preferably formed of thin sheet metal bent into substantially semi-circular form and is of a length to fit over and 70 cover the usual shade curtain roller 11 which is operatively mounted in brackets 12 upon the window casing 13.

This hood 10 is preferably provided with 75 ears or loops 14 cut and raised from the outer surface of the hood forming eyes through which the free ends of the arms 15 of the brackets may be slid, the opposite ends of these arms being secured by screws or otherwise to the window hood 13.

By this construction this cover 13 may be supported directly above the roller and so effectually prevent the dust in the room from settling upon the curtain roller and soiling it. In some instances I provide a lining 17 80 covering the inner face of this hood or cover which lining may be constructed of felt, wool, bristles or any other suitable material, to brush, wipe or remove from the surface of the curtain any dust which may 85 have accumulated thereon, and in some cases when the cover is formed of sheet metal, I roll its edges 18 inwardly over the edges 19 of the lining so as to firmly secure these edges against any possibility of being pulled 90 away during the cleaning action on the roller. In addition I may cement the body surface of the lining to the inner surface of the casing.

By forming the eyes or loops 14 on the 105 dust cover or hood and threading the arms 15 therethrough it will be seen that the hood may be readily slipped off of the ends of the arms and its lining renewed or cleaned and quickly replaced over the roll as often as 110

desired. Then again these arms may be, and preferably are, formed of a flexible or resili-
5 ent material so shaped as to press the cleaning lining on to the outer face of the curtain
and cause it to contact with the outer surface
of the curtain as the diameter of the roller
changes by the curtain being wound upon or
10 unwound therefrom. There is always, even
when the curtain is fully unwound, a line
of contact of sufficient area between the lin-
ing of the hood and the roller to cause the
surface of the curtain to be effectively
15 cleaned.

By the use of my improved device a shade-
15 curtain may be kept clean and so does not
become unsightly and thus its practical
wearing life is materially prolonged.

The foregoing description is directed
20 solely towards the construction illustrated,
but I desire it to be understood that I re-
serve the privilege of resorting to all the
mechanical changes to which the device is
susceptible, the invention being defined and
25 limited only by the terms of the appended
claims.

I claim:

1. A curtain roller cover and cleaner com-
prising a hood adapted to extend along the
length of and cover the roll, said hood being
30 provided with a lining to contact with the
roll to wipe a surface of the curtain on the
roller, and yieldable members for supporting
said hood over the roller and maintaining
35 said hood in contact with the shade on
the roller during the winding and unwinding
of the shade on the roller and pressing

the lining into contact with the surface of
the curtain.

2. A curtain roller cover and cleaner com-
prising a hood adapted to extend along the 40
length of and cover the roller, said hood be-
ing provided with a lining adapted to en-
gage and wipe the surface of the curtain on
the roller, and a pair of supporting arms de-
45 tachably connected to said hood for pressing
the lining into contact with the curtain and
following its changing diameter.

3. A curtain roller cover and cleaner com-
prising a hood adapted to extend along the
length of and cover the roller, said hood be-
ing provided with a lining adapted to en-
gage and wipe the surface of the curtain on
the roller the edges of said hood being
50 rolled inwardly over those of the lining
to bind the latter therein, and a pair of yield-
able arms for supporting said hood on its
roller and maintaining said lines in contact
55 with said hood.

4. A curtain roller cover comprising a
hood of a size to extend around and over the
upper portion of a curtain roller, portions of
the stock of the casing being raised above
60 its normal plane providing loop members on
the surface of said hood, and a pair of arms
each having one end adapted to be connected
to a window casing, and its free end adapted
65 to engage the respective loop members on
said hood to removably support the latter in
operating position over the curtain roll.

In testimony whereof I affix my signature.

GUNNAR H. RYDBERG.
